DOOR LATCH STRUCTURE

George Janonis, Detroit, Mich.

Application October 7, 1946, Serial No. 701,659

15 Claims. (Cl. 292—223)

1

This invention relates generally to door latch structures and refers more particularly to handle assemblies adapted for use with vehicle door latch mechanism of the type set forth in United States Letters Patent No. 2,302,032 and 2,314,400 respectively.

One of the essential objects of the invention is to provide an outside handle assembly wherein the operating handle for the latch mechanism lies substantially flat against the outside of the door so as to normally be out of the way and thereby relieve the door from objectionable protuberances, and is preferably in the form of an elongated finger piece that is mounted at one side of the window opening in the door so as to swing in a plane substantially parallel to the outside of the door from an upright position substantially parallel to an edge of said window opening to an inclined position overhanging said edge so that initially the latch bolt of the door latch mechanism will, during said swinging movement, be released from its keeper, and thereafter an end of the handle may be grasped in the window opening and used as a pull element to open the door.

Another object is to provide a handle assembly wherein the operating handle is so constructed that it normally serves in its upright position as a cover plate for and conceals its mounting means and thereby provides a very neat appearance upon the outside of the door.

Another object is to provide a handle assembly wherein the operating handle is operatively connected in such a way to the door latch bolt that the spring means employed for normally holding the latch bolt in an operative position for proper latching engagement with its keeper is also utilized to normally hold the operating handle in its upright position over its mounting means.

Another object is to provide a handle assembly wherein the operating handle may be rendered inoperative from the inside of the door by means of a knob actuated member that may be engaged with said handle without being accessible or seen from the outside of the door.

Another object is to provide a handle assembly that is simple in construction, economical to manufacture, easy to install and efficient in operation.

Other objects, advantages and novel details of construction of this invention will be made more apparent as this description proceeds, especially when considered in connection with the accompanying drawing, wherein:

Figure 1 is a fragmentary elevation of a vehicle 55 13 and has its outer face substantially flush with

2

door equipped with a handle assembly embodying my invention and showing by dotted lines the position of the operating handle when the latch bolt is released and when the upper end portion of said handle may be used as a pull element for opening the door;

Figure 2 is a fragmentary elevation of the door with the operating handle removed therefrom and showing the mounting plate for said handle and associated parts;

Figure 3 is a fragmentary vertical sectional view taken substantially on the line 3—3 of Figure 1;

Figure 4 is a vertical sectional view taken substantially on the line 4—4 of Figure 3 and showing the operating handle in inclined position after the latch bolt has been released;

Figure 5 is a sectional view taken on the line 5—5 of Figure 1;

Figure 6 is a fragmentary elevation of the outer free edge of the door; and

Figure 7 is a sectional view taken on the line 7—7 of Figure 6.

Referring now to the drawing, A is a vehicle door having a window opening 10, B is a handle assembly embodying my invention, C is a pivotally mounted latch bolt on the free edge portion of the door and engageable with a suitable keeper (not shown), and D is mechanism operable by the handle 11 of the assembly B for actuating the latch bolt C.

As shown, the door A has inner and outer pressed metal panels 12 and 13 respectively spaced laterally apart in the usual manner and having interlocking flanges 14 and 15 respectively at opposite upright edges of the door. Preferably the flanges 14 of the inner panel are substantially L-shape in cross section and span the space between the panels. The flange 15 of the outer panel is crimped over the leg 16 of the L-shaped flange 14 and may be welded thereto if desired.

The handle assembly B embodying my invention is upon the outer panel 13 of the door and preferably comprises the operating handle 11 aforesaid, a mounting plate 17 therefor, a pin 18 operable by a knob 19 from the inner side of the door for rendering the handle 11 inoperative, and a tubular guide sleeve 20 for said pin. As shown, the handle 11 comprises an elongated bar of substantially T cross section that is pivoted adjacent one end thereof at 21 to the mounting plate 17. The mounting plate 17 is secured within an inwardly depressed portion 22 of the outer panel 13 and has its outer face substantially flush with

the outer surface of the outer panel. Preferably the shape of the plate 17 and base 23 of the handle is substantially identical; however the base 23 is slightly oversize relative to said plate so as to cover and conceal the same when the parts are in registration. Moreover, the construction is such that the base 23 of the handle lies substantially flat against the outer surface of the outer panel 13 during its pivotal movement over the mounting plate 17. Thus, the handle 11 is not apt to catch clothing of persons passing close to the door.

In the present instance the construction of the handle 11 is such that the longitudinal rib 24 thereof may be grasped by the fingers of the operator to swing the handle about its pivot 21 from the normal upright position in registration with the mounting plate 17 to an inclined position (shown by dotted lines in Figure 1) overhanging the adjacent edge 25 of the window opening 10 in the door so that the upper end portion 26 of said handle may be grasped in the window opening and used as a pull element to open the door.

The pin 18 is slidable in the guide sleeve 20 and in an opening 27 in the mounting plate 17 to and from engagement with a suitable socket 28 in the back of the base 23 of the handle and may be conveniently operated by the knob 19 rigid with said pin. The guide sleeve 20 extends between and is terminally secured to the inner panel 12 and to the depressed portion 22 of the outer panel. Thus, this sleeve 20 not only guides the pin 18 but also serves as a structural reinforcement for the panels 12 and 13 respectively of the door.

The latch bolt C is wedge-shaped in configuration and is mounted to swing over the flange 14 forming the outside free edge of the door. Preferably the head 30 of the wedge-shaped bolt is rounded and has a laterally extending cylindrical shank 31 that extends inwardly through the free edge of the door and is journaled in a bearing 32 formed by complementary semi-circular portions 33 and 34 respectively of case plate sections 35 and 36 upon the inside and rigid with the free edge of the door. Such sections 35 and 36 are preferably L-shape in cross section and are secured to each other as well as to the free edge of the door. Preferably the webs 37 and 38 respectively of said sections are secured together in back to back relation, while the lateral flanges 39 and 40 respectively of said sections are secured to the door.

For normally retaining the tapered tail portion 41 of the latch bolt in lowered keeper engaging position, I have provided the shank 31 of the bolt with diametrically extending pins 42 and 43 respectively and coil springs 44 and 45 respectively that extend in opposite directions from said pins and are connected by bolts 46 and 47 anchored in the webs 37 and 38 of the case plate sections 35 and 36.

The mechanism D operable by the handle 11 for actuating the latch bolt C from the outside of the door comprises a T-shaped pin or stud 50 on the back of the handle, and a long link 51 terminally connected to the T-shaped pin 50 and to the pin 42 on the shank 31 of the latch bolt C. As shown in Figure 2, the stem 52 of the T-shaped pin 50 is located in an elongated slot 53 in the outer panel 13 and is adapted to travel lengthwise of said slot when moved by pivotal action of the handle 11. By referring to Figure 3 it will be noted that the handle 11 normally overlies

the slot 53 and conceals the same. The link 51 has an opening 55 receiving the pin 42 on the bolt shank 31 and has an elongated slot 56 receiving the stem 52 of the T-shaped pin on the handle 11 so that the link 51 and bolt C may move independently of the handle 11 when the door is slammed or pushed to closed position. Thus, when the handle 11 is swung on its pivot 21 from the full line position to the dotted line position (Figure 1) the link 51 will lift the pin 42 and thus cause the latch bolt C to be rotated against the tension of the springs 44 and 45.

Any suitable remote control mechanism (not shown) may be connected to the pin 43 on the shank 31 of the latch bolt to actuate the latter from the inner side of the door.

Preferably a lug 60 is provided on the mounting plate 17 to serve as a stop for the handle 11. As shown, this lug 60 engages a recess 61 in the handle 11 so as to be normally concealed. Due to the link connection between the T-shaped pin 50 on the handle and the pin 42 on the bolt shank, it will be apparent that the springs 44 and 45 for the latch bolt C will hold the handle 11 against the stop lug 60 so that said handle is normally in registry with the mounting plate 17 and conceals the slot 53 in the outer panel 13.

What I claim as my invention is:

1. A latch structure for a door, comprising a latch bolt at one edge of said door, means for actuating said latch bolt including a pivotally mounted operating handle lying substantially flat against the outer side of said door, and means operable from the inner side of said door for rendering said actuating means inoperative including a knob actuated pin slidably transversely of said door and engageable with a socket in the back of said handle.

2. A latch structure for a door having inner and outer panels, comprising a latch bolt carried by a portion of one of said panels, means for actuating said latch bolt including an operating handle mounted for pivotal movement over the outer panel, means for rendering said actuating means inoperative including a pin slidably transversely of both panels and engageable with said handle, and a guide for said pin extending between and terminally secured to both of said panels and constituting a reinforcing member therebetween.

3. A latch structure for a door having an outer panel provided with an opening and an inwardly depressed portion, comprising a latch bolt at an edge of said door, an operating handle upon the outer side and substantially parallel to said outer panel, a mounting plate for said handle substantially parallel thereto and anchored within said depressed portion, a pivot for said handle extending transversely of said plate, a pin on said handle projecting inwardly through the opening in said outer panel, and an operating connection between said handle and latch bolt including a member upon the inner side of and substantially parallel to said outer panel, said member having a lost motion connection with said pin.

4. A latch structure for a door having an outer panel provided with an opening, comprising a latch bolt at an edge of said door, an operating handle upon the outer side of and substantially parallel to said outer panel, a mounting plate for said handle substantially parallel thereto and carried by said outer panel, a pivot for said handle extending transversely of said plate, a projection on said handle extending inwardly

through the opening in said outer panel, and an operating connection between said handle and latch bolt including a member upon the inner side of and substantially parallel to said outer panel, said member being connected directly to said projection.

5. A latch structure for a door having inner and outer panels, comprising a latch bolt at one edge of said door, a guide sleeve extending between and terminally secured to said inner and outer panels, means for actuating said latch bolt including an operating handle upon the outer side of said outer panel, and means operable from the inner side of said inner panel for rendering said actuating means inoperative including a pin slidable in said guide sleeve and engageable with said handle.

6. A latch structure for a door having a window opening, comprising a latch bolt at one edge of said door, and means for actuating said latch bolt including an elongated operating handle lying substantially flat against the outer side of said door in a position substantially parallel to an edge of said window opening, and means mounting said handle so that it may swing in a plane substantially parallel to the outside of said door from the position aforesaid to a position overhanging an edge of said window opening, whereby the overhanging portion of said handle may be grasped in said opening and used as a pull element to open the door, said mounting means including a mounting plate on the outer side of said door, and a pivot for said handle disposed perpendicular to the plane of movement of said handle and carried by said mounting plate, the construction and arrangement of said handle and mounting plate relative to each other being such that said handle normally covers and conceals said mounting plate and pivot aforesaid.

7. A latch structure for a door having a window opening, comprising a latch bolt at one edge of said door, and means for actuating said latch bolt including an elongated operating handle lying substantially flat against the outer side of said door in a position substantially parallel to an edge of said window opening, and means mounting said handle so that it may swing in a plane substantially parallel to the outside of said door from the position aforesaid to a position overhanging an edge of said window opening, whereby the overhanging portion of said handle may be grasped in said opening and used as a pull element to open the door, said mounting means including a mounting plate on the outer side of said door, and a pivot for said handle disposed perpendicular to the plane of movement of said handle and carried by said mounting plate, the construction and arrangement of said handle and mounting plate relative to each other being such that said handle normally covers and conceals said mounting plate and pivot aforesaid, and means operable from the inner side of said door for rendering said handle inoperative, including a knob actuated member movable through said mounting plate and engageable with said handle without being accessible or seen from the outside of the door.

8. A latch structure for a door, comprising a latch bolt at one edge of said door, and means for actuating said latch bolt including an operating handle lying substantially flat against the outer side of said door, means mounting said handle so that it may swing in a plane substantially parallel to the outside of said door, said

mounting means including a mounting plate secured within an inwardly depressed portion of the outer side of said door, and a pivot for said handle disposed perpendicular to the plane of movement of said handle and carried by said mounting plate, the construction and arrangement of said handle and mounting plate relative to each other being such that said handle normally covers and conceals said mounting plate and pivot aforesaid.

9. A latch structure for a door, comprising a latch bolt at one edge of said door, and means for actuating said latch bolt including an operating handle lying substantially flat against the outer side of said door, means mounting said handle so that it may swing in a plane substantially parallel to the outside of said door, said mounting means including a mounting plate upon the outer side of said door, and a pivot for said handle disposed perpendicular to the plane of movement of said handle and engaging said mounting plate, and means for holding said handle over said mounting plate, including a lug on said mounting plate normally concealed by said handle and engageable with a recess in said handle.

10. A latch structure for a door, comprising a latch bolt at one edge of said door, and means for actuating said latch bolt including an operating handle lying substantially flat against the outer side of said door, means mounting said handle so that it may swing in a plane substantially parallel to the outside of said door, said mounting means including a mounting plate upon the outer side of said door, and a pivot for said handle disposed perpendicular to the plane of movement of said handle and engaging said mounting plate, a guide sleeve extending between and terminally secured to the inner and outer sides of said door, said mounting plate having an opening and said handle having a socket normally in registration with the outer end of said guide sleeve, and means operable from the inner side of said door for rendering said handle inoperative, including a knob actuated member slidable in said guide sleeve and in said registering opening and socket.

11. A latch structure for a door, comprising a latch bolt at one edge of said door, and means for actuating said latch bolt including an operating handle lying substantially flat against the outer side of said door, means mounting said handle so that it may swing in a plane substantially parallel to the outside of said door, said mounting means including a mounting plate upon the outer side of said door, and a pivot for said handle disposed perpendicular to the plane of movement of said handle and engaging said mounting plate, a structural reinforcement for said door extending between and secured to the inner and outer sides of said door, and means operable from the inner side of said door for rendering said handle inoperative, including a knob actuated member slidably engaging said structural reinforcement and movable through said mounting plate into engagement with said handle without being accessible or seen from the outside of the door.

12. A latch structure for a door having a window opening, comprising a latch bolt at one edge of said door at a point remote to said window opening, and means for actuating said latch bolt including an elongated operating handle having a pivot normal to one side of said door and located adjacent said window opening, the length

of said handle from one end portion thereof to said pivot being greater than the distance between said pivot and said window opening whereby said end portion may be swung about said pivot from a position overlying said side of said door to a position overhanging an edge of said window opening, said handle being disposed in such close substantially parallel relation to said side of said door that the back of said end portion is inaccessible when said end portion is in said overlying position but is accessible in said window opening and is adapted to be used as a pull element to open the door when said end portion is in said overhanging position.

13. A latch structure for a door having a window opening, comprising a latch bolt at one edge of said door at a point remote to said window opening, means for actuating said latch bolt including an elongated operating handle having a pivot normal to one side of said door and located adjacent said window opening, and means operable from the other side of said door for rendering said actuating means inoperative including a pin slidable transversely of said door and engageable with said handle.

14. A latch structure for a door having a window opening, comprising a latch bolt at one edge of said door at a point remote to said window opening, means for actuating said latch bolt including an elongated operating handle having a pivot normal to one side of said door and located adjacent said window opening, the length of said handle from one end portion thereof to said pivot being greater than the distance between said pivot and said window opening whereby said end portion may be swung about said pivot from a position overlying said side of said door to a position overhanging an edge of said window opening, said handle being disposed in such close substantially parallel relation to said side of said door that the back of said end portion

is inaccessible when said end portion is in said overlying position but is accessible in said window opening and is adapted to be used as a pull element to open the door when said end portion is in said overhanging position, and means including an outward projection on the front of said handle for swinging said handle about said pivot between the two positions mentioned.

15. A latch structure for a door having inner and outer panels, comprising a tubular member extending between and terminally connected to said inner and outer panels, a mounting plate on one of said panels and having an opening registering with one end of said tubular member, a latch bolt at one edge of said door, means for actuating said bolt including an operating handle pivoted on said plate and having a socket adapted to register with said opening, and means for rendering said handle inoperative including a pin slidable in said tubular member through said opening and engageable with said socket.
